UNITED STATES PATENT OFFICE.

PAUL CUMMING, OF KEYWEST, FLORIDA.

CUFF-HOLDER.

SPECIFICATION forming part of Letters Patent No. 697,328, dated April 8, 1902.

Application filed November 14, 1901. Serial No. 82,301. (No model.)

To all whom it may concern:

Be it known that I, PAUL CUMMING, a citizen of the United States, and a resident of Keywest, in the county of Monroe and State 5 of Florida, have invented a new and Improved Cuff-Holder, of which the following is a full, clear, and exact description.

The object of this invention is to provide a novel, simple, and very reliable cuff-holder, 10 easy to apply and remove, light, strong, and neat in appearance, and that may be manufactured at a low cost.

The invention consists in the novel construction and combination of parts, as is 15 hereinafter described, and defined in the appended claims.

Reference is to be had to the accompanying drawings, forming a part of this specification, in which similar characters of reference indicate 20 corresponding parts in all the figures.

Figure 1 is a perspective view of the cuff-holder applied. Fig. 2 is a plan view of parts of the cuff-holder separated. Fig. 3 is a side view of the cuff-holder, and Fig. 4 is an enlarged 25 perspective view of the portion of the device that engages the cuff when applied.

The cuff-lock, which in use is detachably secured to a shirt-cuff and is an essential novel detail of the invention, is constructed as follows: A locking-plate 10 is provided, consisting of a flat planchet cut from resilient sheet metal and preferably given an ovate or heart-shaped contour. At the transverse center of the plate 10 an opening *a* is formed near the 30 widest end, and from said opening two parallel slits *b* are cut in the plate, extending of a suitable length toward the opposite end of the plate, that is substantially arrow-shaped. The formation of the slits in the plate 10 releases an intermediate strip of the resilient metal, thus affording a spring latch-tongue *c*, as clearly shown in Figs. 2 and 4, and it will be seen that a transverse bar *d* is formed at the opening *a* and is spaced from the free end 35 of the latch *c* by said opening. A ring-eye *e* is formed on one end 11^a of the arm 11, that is bent at or near a right angle between its ends, as indicated at *g* in Figs. 3 and 4. Upon the inner end of the arm 11 a tubulation 40 45 50 11^b is formed or secured, this hollow cylindrical part of the arm having annular beads *h* *h'* formed, respectively, upon the outer and

inner terminations of the same. The locking-plate 10 is held to rock upon the ring-eye *e* by a loose engagement of the latter with the 55 cross-bar *d*, and in the periphery of the ring-eye two notches *f* *f'* are formed, that may be separately engaged with the free end of the spring latch piece or tongue *c*. The notches *f* *f'* are spaced apart and so respectively positioned that when the latch-tongue *c* is engaged with the notch *f* the locking-plate 10 will be held projected substantially at a right angle to the upright member of the bent arm 11, as indicated in Figs. 3 and 4, which is the 60 65 locked position for the plate 10 when the device is secured upon a shirt-cuff, as will be hereinafter more fully explained.

As indicated in Fig. 3 by dotted lines, the plate 10 may be rocked into an upright position and the free end of the latch-tongue *c* be seated in the notch *f'* as occasion may require, this adjustment of the locking-plate nearly aligning it with the upright member 11^a of the bent arm 11. 70 75

Two clasping-arms are completing members of the improvement, and, as shown, one arm 12 consists of an elongated strip of resilient plate metal, shaped marginally as represented in Fig. 2. 80

The body portion of the clasping-arm 12 is parallel on its edges and is formed at one end with a lateral clasping-finger 12^a and at the opposite end with a rectangular member 12^b. 85

A coacting arm 13 is formed integral with the body of the clasping-arm 12 by slitting the material, as shown in Fig. 2 at *i*, and a clasping-finger 13^a is laterally formed on the arm 13 and extends into the lateral clasping-finger 12^a. The slit *i* extends from a point 90 near the rectangular member 12^b parallel with the marginal edge of the arm 12 and the lateral finger 12^a thereon, thus providing an integral connection *i'* between the arms 12 13 near the member 12^b. 95

The two coacting arms 12 13 are bent into wave form, producing two curves *m* *m'* on the arms at a suitable distance from one end member 12^b, and between these oppositely-positioned curves a spacing-bar *n* is transversely 100 secured.

At a proper distance from the cross-bar *n* two wave curves *o* *o'* are formed on the arms 12 13, and it will be evident that pressure ap-

plied upon these curved portions of the arms 12 13 will cause their free ends to diverge.

The adjacent surfaces of the lateral fingers 12^a 13^a are roughened, preferably by cross- 5 checking with slight grooves, as shown at *r* in Fig. 2, or a toothed surface of any other kind may be employed to hold the ends of the fingers engaged with material of the shirt-sleeve.

10 Upon the free transverse edge of the rectangular end plate 12^b a spring-finger 12^c is formed by cross-slitting the material, and on the free end of said finger a toe *s* is outwardly bent.

15 The rectangular end piece 12^b is formed into a cylindrical sleeve and is fitted loosely upon the tubulation 11^b, said sleeve having one end loosely engaged with the bead *h* and the spring-finger 12^c pressed upon the bead 20 *h'*, so that the toe *s* may enter an indentation in the adjacent edge of the bead *h'*, and thus restrain the clasping-arm from too-free rocking movement on the bent arm 11.

In use the locking-plate 10 is first adjusted 25 as indicated by dotted lines in Fig. 3, which projects the free end outward from the upright member of the bent arm 11 and enables the insertion of the locking-plate through the buttonholes in the shirt-cuff. After passing 30 the locking-plate through the buttonholes of the cuff the plate may be held from accidental displacement by turning it at right angles to the member 11^a of the arm 11 and engaging the end of the latch-tongue *c* with the notch 35 *f*, as before explained. The cuff A being thus connected with the holder device, it may be detachably secured upon the wristband B of a shirt-sleeve B' by first spreading apart the clasping-fingers 12^a 13^a, effected by compression of the curved projections *o o'*, and then engaging these lateral members of the arms 12 13 with one edge of the sleeve-vent B², as shown in Fig. 1, a release of pressure on the arms 12 and 13 permitting the fingers to clasp 45 the shirt-sleeve, and thus secure the cuff A in place on the wrist of the wearer.

It will be seen that the swiveled connection of the clasping-arms 12 13 effected by the sleeve 12^b and tubulation 11^b, rockably engaged, as hereinbefore described, permits an easy rotatable adjustment of the cuff on the wristband of the shirt-sleeve as may be desired to properly dispose its lapped edges at the side of the hand of the wearer.

55 The parts of the improved cuff-holder are few, simple, and readily manufactured by ordinary means, so that the device may be produced at a low cost and afford a neat and inexpensive cuff-holder for general use.

60 Having thus described my invention, I claim as new and desire to secure by Letters Patent—

1. A cuff-holder, comprising two clasping-arms having opposed fingers on their free 65 ends, a longitudinally-extended sleeve at the

opposite ends of said arms, a bent arm having a cylindrical end on which the sleeve is loosely mounted, means to restrict end play of the sleeve on one end of the arm, and a locking-plate held to rock on the other end of the bent arm. 70

2. A cuff-holder, comprising two clasping-arms formed one within the other, said arms having laterally-extended fingers at like ends of the arms, and oppositely-bent curves thereon between the ends of the arms, a sleeve having a spring-finger at one edge, a bent arm having a tubulation at one end whereon spaced beads are formed, the spring-finger 75 engaging one of said beads, and a locking-plate held to rock on a ring-eye formed on the opposite end of the bent arm. 80

3. A cuff-holder, comprising a bent arm having a ring-eye on one end, a locking-plate held to rock on the ring-eye and having a 85 spring-tongue adapted to engage its free end in notches formed in the edge of the ring-eye, a tubulation on the opposite end of the bent arm, having a bead at each end, two clasping-arms formed one within the other and 90 having clasping-fingers adapted to press one toward the other, a sleeve on the opposite end of the clasping-arms, said sleeve being fitted upon the tubulation and having a finger adapted to bear on one of the beads, and undulations in the clasping-arms, which when compressed are adapted to spread apart the clasping-fingers. 95

4. A cuff-holder comprising an arm bent at a right angle and having a ring-eye on one 100 end, a locking-plate held to rock on said arm upon said ring-eye, a latch-tongue formed integral with the locking-plate and adapted to engage its free end in either of two notches in the ring-eye, two clasping-arms having 105 clamping members laterally projected at their free ends, and means for rockably connecting the other ends of the arms with the remaining end of the bent arm. 110

5. The combination with an arm bent at a right angle, and two clasping-arms connected together near one end of each arm and having laterally-projected clamping members at similar ends thereof, of a rockable joint between an end of one clasping-arm and an adjacent end of the bent arm, comprising a longitudinally-extended tubulation on the bent arm, a sleeve on the clasping-arm loosely mounted on the tubulation, two bead formations on the tubulation loosely contacting with respective ends of the sleeve, and a spring-finger on one end of the sleeve, adapted to contact with an adjacent bead. 115 120

In testimony whereof I have signed my name to this specification in the presence of 125 two subscribing witnesses.

PAUL CUMMING.
